UNITED STATES PATENT OFFICE

ERNEST J. HORTON, OF PITTSBURGH, PENNSYLVANIA, ASSIGNOR TO RUUD MANUFACTURING COMPANY, OF PITTSBURGH, PENNSYLVANIA, A CORPORATION OF PENNSYLVANIA

CLOSURE

Application filed February 2, 1929. Serial No. 337,115.

This invention relates to doors or similar closures, and more particularly to an improved form of stop for controlling the opening or closing thereof.

5 An object of this invention is to provide a device of the type set forth having an improved construction and arrangement.

A further object is to provide a door stop constructed and arranged to automatically 10 operate upon movement of the door in one direction to prevent return movement thereof until the door check is manually set to permit such return movement.

15 A further object is to provide a device of the type described which will be simple and rugged in construction, positive in operation and cheap to manufacture and assemble.

These and other objects which will be apparent to those skilled in this particular art 20 are attained by means of the invention illustrated in the accompanying drawings in which Figure 1 is a front elevational view of cooperating closure members or doors provided with a stop mechanism constructed in 25 accordance with one embodiment of this invention. Fig. 2 is a top plan view thereof, partly in section, showing the mechanism in operative door holding position.

The particular embodiment of the present 30 invention which has been chosen for the purpose of illustration, is shown in connection with an opening 5 which may be partially or completely closed by one or more closure members such as the cooperating doors 6 hinged to a supporting frame 7 by means of 35 pins 8 engaging hinge pin lugs 9 on the doors and similar pin lugs 10 on the frame. In the present construction door closing springs 11 are employed for normally pressing 40 the doors into closed position.

As illustrated, the door holding mechanism is so formed as to operate automatically upon opening the doors 6, against the pressure of the springs 11, so as to hold the doors 45 in open position until access to the opening 5 is no longer desired, at which time the check or stop can be manually set to permit closing of the door under spring pressure.

This mechanism consists of a stop 12 slidably 50 mounted upon the hinge pin 8 or any other

similar supporting means and provided with a tongue 13, which is adapted to be received within a slot 14 formed in the door, when the stop is raised to a position opposite such slot. It will be apparent that when 55 in this position the slot and stop cooperate to permit closing of the door. The stop itself is so formed and its dimensions are such that opening the door 6 causes the stop receiving recess 14 to swing away from the stop and 60 free the latter from the confines thereof. This permits the stop to slide downwardly by gravity and away from the recess into the position illustrated at the left in Fig. 2 65 wherein the stop is located between the edge of the door 6 and the door frame so as to prevent closing of the door.

To close the door it is merely necessary to free the stop from the pressure of the door 70 so that it can be raised manually to a position opposite the recess 14, at which time the door may be closed. The movement of the stop by gravity upon opening of the door is such as to direct the operator's attention thereto, so that, even with one unfamiliar 75 with the particular form of stop mechanism employed, his attention is so directed to the stop by its movement that he is immediately informed thereby of the manner of its operation and the necessary step to permit closing 80 of the door.

What I claim as new and desire to secure by Letters Patent is:

1. The combination with a support having a door hingedly mounted thereon, of a stop 85 slidably mounted on the pin of said door hinge and movable by gravity into position between said door and said support when said door is open to prevent closing thereof.

2. The combination with a door and a frame to which said door is hinged, of a stop 90 slidably mounted on the pin of said hinge, means on said door for holding said stop in inoperative position when said door is closed, said means being formed so as to release said stop to permit movement thereof into position between said door and said frame when said door is opened.

3. The combination with a door and a frame to which said door is hinged, of a 100

vertical rod adjacent the hinged side of said door, a stop slidably mounted on said rod, and adapted to drop between said door and said frame to prevent the closing of said door, said door having a slot adjacent the upper portion of said rod for receiving said stop to permit closing of said door.

4. The combination with a door and a frame to which said door is hinged, of a stop slidably mounted on the pin of said door hinge and adapted to drop by gravity into position between said door and said frame when said door is open to prevent the closing thereof; said door having a slot slightly below the upper hinge on said door for receiving said stop when raised adjacent thereto to permit the closing of said door.

5. The combination with a door and a frame to which said door is hinged, of a stop slidably mounted adjacent the hinged side of said door, a slot in said door for receiving said stop when said door is closed, said slot being formed to release and to permit said stop to drop between said door and said frame when said door is open for preventing the closing of said door.

6. The combination with a frame, of a door hinged thereto and provided with a slot adjacent to the hinge, an interlocking member slidably mounted adjacent the hinged side of the door and adapted to be received in said slot when said door is closed, said slot being formed to release and to permit said stop to drop downwardly between said frame and said door when said door is opened to prevent the closing thereof.

In testimony whereof, I have hereunto subscribed my name this 31st day of January, 1929.

40 ERNEST J. HORTON.
